[57] CLAIM

The ornamental design for a sandal upper, as shown and described.

DESCRIPTION

FIG. 1 is a perspective view of a sandal upper showing my new design;

FIG. 2 is a top plan view thereof;

FIG. 3 is a right side elevational view thereof;

FIG. 4 is a front elevational view thereof;

FIG. 5 is a left side elevational view thereof;

FIG. 6 is a rear elevational view thereof; and,

FIG. 7 is a perspective view of a second embodiment, all parts being identical to the first embodiment, except for a plain top (no seam).

The broken line showing of a sole in FIGS. 1-7 is for illustrative purposes only and forms no part of claimed design.
